UNITED STATES PATENT OFFICE

JAMES M. LABAUGH, OF PATERSON, NEW JERSEY, ASSIGNOR TO AMERICAN TELEPHONE AND TELEGRAPH COMPANY, A CORPORATION OF NEW YORK

DESIGN FOR A CASING FOR A TELEPHONE-SUBSTATION SET

Application filed June 4, 1930. Serial No. 35,901. Term of patent 14 years.

To all whom it may concern:

Be it known that I, JAMES M. LABAUGH, a citizen of the United States, residing at Paterson, in the county of Passaic, State of New Jersey, have invented a new, original, and ornamental Design for a Casing for a Telephone-Substation Set, of which the following is a specification, reference being had to the accompanying drawing, forming a part thereof.

The figure is a perspective view of a casing for a telephone substation set, showing my new design.

I claim:

The ornamental design for a casing for a telephone substation set, as shown.

In witness whereof, I hereunto subscribe my name this 29th day of May, 1930.

JAMES M. LABAUGH.
